DISPOSABLE RAZOR

Albert D. Brown, Atlanta, Ga.

Application November 19, 1945, Serial No. 629,367

7 Claims. (Cl. 30—32)

1

My invention relates to an improvement in shaving devices or safety razors, and has for one purpose to provide a dispensable razor or shaver.

Another purpose is to provide a razor or shaver adapted for a quick and emergency shave for those who find themselves without the usual shaving facilities.

Another purpose is to provide a packaged shaver which includes or carries enough brushless cream for one shave.

Another purpose is to provide an improved package assembly for dispensable shavers.

Other purposes will appear from time to time in the course of the specification and claims.

I illustrate the invention more or less diagrammatically in the accompanying drawings wherein Fig. 1 is a perspective view;

Figure 2 is a similar perspective illustrating the shaver as cut away along the section line 2—2 of Fig. 1;

Figure 3 is a perspective view of the shaver from a different angle, with a brushless cream container in the removed position.

Figure 4 is a perspective view illustrating a group of packaged shavers arranged in a stack; and

Figure 5 is a perspective view of a single container with its cover partly opened, and with the shaver indicated within the container.

Like parts are indicated by like symbols throughout the specification and drawings.

Referring to the drawings, 1 generally indicates a shaver body generally "comma" shaped in longitudinal section, shown as having a tubular portion, 2 with a generally cylindrical aperture, 3 which may be open at one or at both ends. The body has a handle flange or projection 4, one side of which is defined by a convex curved surface 5, shown as continuous with a generally or partially cylindrical surface 2a surrounding the cylindrical portion 2 of the body. The opposite concave face 6 of the member 4 is joined by an arcuate connecting surface 7 to the more or less cylindrical surface 2a of the body 2. The ends 8 of the body 2 may be plane and parallel. One plane face is shown at 8 in Figure 1. The interior aperture 3 opens to the exterior curved face 5 through a drainage slot 9, shown for example in Figure 2. Located at one side of the slot 9, and preferably permanently molded into the body 1, is a razor blade 10 having a sharpened edge 11. The outer edges of the drainage slot 9 terminate in beveled flattened portions 12, 13. The parts are so proportioned in relation to the cutting edge 11 of the blade 10, that the

2

blade is properly placed and protected to obtain a safety razor effect. The corners, or ends of the blade are inset in the body 1, and the cutting edge is located below or within the curved surface 5. It will be noted that the handle portion, or flange 4, is so formed and positioned, in relation to the slot 9 and the razor edge 11, that the user can operate the razor by grasping the handle with his fingers and drawing the body portion across the face in any desired direction. I find it desirable to position within the aperture 3 a supply of shaving cream. For example, as shown in Figs. 1 and 3, I illustrate a capsule formed of the telescoped parts 20 and 21, which contains enough brushless shaving cream for at least one shave.

The body 1 may be formed of any suitable material. I may employ any suitable plastic, for example, a transparent plastic. I prefer to employ a cheap material in order that the unit may be so priced as to make it practical and economical to use it once and then throw it away. It will be understood, however, that under some circumstances it may be practical to so mount the blade 10 that it can be removed and replaced. For example, where slightly elastic material is employed for the body, 1, the blade may be removably held frictionally in place at the proper location for shaving. However, I prefer to employ my invention in connection with a disposable shaver, in which the blade is permanently molded into the body, and in which the whole unit may be discarded after a single use.

In dispensing the device, I prefer to provide a sealed container shaped to protect the cutting edge of the blade and to provide minimum stacking space. Referring to Figs. 4 and 5, I illustrate a container which may be of any suitable material such as a transparent plastic, or of opaque material with cellophane or otherwise transparent window portions. With reference to Fig. 5, I illustrate the container as having a rear end wall 30 of maximum height and a front end wall 31, of minimum height, and connecting side walls 32 which have inclined upper edges 33 from which folds or tabs 34 are inwardly folded. The cover 35 is bent or hinged as at 36 to the upper edge of the end wall 30 and has a forward flap 37 which may be inserted between the adjacent edges 30 of the flaps 34 and the end wall 31. A removal tab 31a may be used. It will be observed that when the container thus formed is closed, it holds the dispensable shaver unit in position with the blade edge 11 located in the bottom or corner space 38 of the container, where it is out of con-

tact with the container itself and protected by the container. It will be understood that before inserting the shaver in the container, the shaver may be sterilized and the edge of the blade 11 protected by an oil film. The container, which may be readily formed from a single piece or blank, may be sealed in the closed position. Preferably it is made airtight, for example through the medium of any suitable sealing tape. Any suitable tab 31a may be provided to permit the easy opening of the container.

The above described container is so proportioned that it can be stacked in pairs, each pair forming together a rectangular body as shown at small a, small b of Fig. 4. As many pairs as desired, arranged to form such rectangular bodies, may be stacked or packaged in a large container. In Fig. 4 I illustrate six containers arranged in three pairs, which, after being stacked or assembled, may be packaged or handled as a larger unit. Also they may be loosely stacked, as shown in Fig. 4, for handy disposition in a show case or on a counter.

It will be realized that whereas I have described and illustrated a practical and operative device, nevertheless many changes may be made in the size, shape, number and disposition of parts, without departing from the spirit of my invention. I therefore wish my description and drawings to be taken as in a broad sense illustrative or diagrammatic, rather than as limiting me to my precise showing.

The use and operation of the invention are as follows:

My dispensable shaver is adapted to provide a quick emergency shave for those who find themselves without the usual shaving facilities. The shaver is shown as formed with a single plastic body, generally indicated at 1 with an integral concave-convex handle, and an aperture 3 in which the cream capsule 20, 21 is stored. In order to remove the capsule all that the user has to do is to tilt the body 1 and to permit the capsule to drop out by gravity. The user then separates the capsule parts 20, 21 and applies the cream to his face. The inside curved surface 6, 7 provides an efficient resting place for the second joint of the second finger, the thumb and index finger, grasping the ends of the body 1. For shaving the upper lip downwardly the handle portion 4 of the body may be grasped with the thumb on the convex side and the index and second finger on the concave side. For shaving upwardly the shaver body is inverted and the index finger is placed on the concave curved portion 6, 7 with the thumb and second finger grasping the ends of the body. Thus, I have provided a simple, small, compact shaving body which is adapted for shaving in a variety of directions and with a variety of finger positions. The general contour of the shaver, in connection with the fact that the edge 11 has no exposed corners and is located within the curved surface 5, makes the likelihood of injury less than that arising from the use of the conventional safety razors now on the market. The shaver can be supplied as a sterilized article and can therefore be stored for long periods without deterioration. The blade is protected from rust by the oil film, and the shape of the container, as shown in Figs. 4 and 5, is such that the shaver and its blade are protected from injury in handling. The unit is self-contained and includes its supply of brushless cream. It is ideally adapted for sale or dispensing in drug stores, hotel lobbies, news stands, vending ma-

chines, hotel wash rooms, air line, railroad and bus terminals and club locker rooms. It is also a handy article for travelers to carry to protect themselves from emergency. A supply may also be kept in a private home to care for unexpected visitors.

I claim:

1. In a dispensable shaver, a body portion having an integral handle extending therefrom, said body portion and handle having, in longitudinal cross section, the general form of a comma, the generally cylindrical part of the comma having an aperture opening outwardly to an end of the body portion, the body portion having a slot extending from said aperture to the major convex face of the comma, and a blade inset in said body portion along said slot said blade having a cutting edge located within the curvature of said convex face of the comma, the face of the body portion being recessed, along each side of said slot, said recesses forming a space in which the edge of said blade is located.
2. In a disposable shaver, a body portion and a handle therefor, said body portion having an internal aperture and a slot extending from said internal aperture to an outer surface of the body portion, and a blade fixed in and extending along said slot, the surface of said body portion to which said slot extends being concave.
3. In a disposable shaver, a body portion having a curved outer surface with a recess in said surface, and a blade permanently secured in said body, said blade having an edge located in said recess and within the contour defined by the curvature of said outer surface.
4. In a disposable shaver, a body portion having a curved outer surface with a recess in said surface, and a blade permanently secured in said body, said blade having an edge located in said recess and within the contour defined by the curvature of said outer surface, said body being generally cylindrical, with its axis generally parallel with the edge of the blade.
5. In a disposable shaver, a body portion having a curved outer surface with a recess in said surface, and a blade permanently secured in said body, said blade having an edge located in said recess and within the contour defined by the curvature of said outer surface, said body being generally cylindrical, with its axis generally parallel with the edge of the blade, and an integral handle extending generally tangentially from said body portion.
6. In a disposable shaver, a body portion having a curved outer surface with a recess in said surface, and a blade permanently secured in said body, said blade having an edge located in said recess and within the contour defined by the curvature of said outer surface, said body being generally cylindrical, with its axis generally parallel with the edge of the blade, and an integral handle extending generally tangentially from said body portion, said handle having a concave surface and an opposite convex surface generally continuing the outer cylindrical surface of the body portion, said blade, and the recess in which it is positioned, being located adjacent the junction of the convex surface of the handle with the cylindrical surface of the body portion.
7. In a disposable shaver, a body portion generally cylindrical in cross section, an integral handle extending from one side and throughout the entire length of the cylindrical portion, the body and handle in transverse cross section having the appearance of a comma, the handle form-

ing the tail of the comma and being pointed by a major convex face tangent to the cylindrical portion of the body and a minor concave face located between the tail of the comma and the cylindrical portion, a cylindrical aperture extending through the cylindrical portion of the comma from end to end, and a slot extending through the wall of the cylindrical portion between the cylindrical aperture and the major concave face of the comma, a blade held in the body of the 10 shaver and overlying the slot, the convex face of the body in front of the blade being reduced in thickness to provide clearance for the blade, such clearance terminating at the slot.
